UNITED STATES PATENT OFFICE.

ALVIN D. BROWN, OF NORWICH, NEW YORK.

COLLAPSIBLE CRATE OR RECEPTACLE.

1,171,924.

Specification of Letters Patent. Patented Feb. 15, 1916.

Application filed February 19, 1915. Serial No. 9,409.

To all whom it may concern:

Be it known that I, ALVIN D. BROWN, a citizen of the United States, residing at Norwich, in the county of Chenango and State of New York, have invented certain new and useful Improvements in Collapsible Crates or Receptacles, of which the following is a specification, reference being had to the accompanying drawings.

10 This invention relates to collapsible crates or receptacles, and has for its primary object to provide a device of this character wholly constructed of wire, which is particularly designed as a container or bin for potatoes 15 or other farm products.

It is an additional object of the invention to provide a collapsible crate or receptacle which is extremely strong and durable, may be easily and quickly collapsed or set up in 20 condition for use, and when collapsed, will occupy but small storage space.

The invention has for a further general object to produce a crate of the above character which is light in weight and may be 25 readily moved from place to place and can also be produced at small manufacturing cost.

With the above and other objects in view, my invention consists in the novel features 30 of construction, combination, and arrangement of parts to be hereinafter more fully described, claimed, and illustrated in the accompanying drawing, in which,

Figure 1 is a perspective view of my improved collapsible crate embodying the preferred form; Fig. 2 is a vertical section; and Fig. 3 is a perspective view showing the crate collapsed.

Referring in detail to the drawing, 5 and 40 6 designate the top and bottom wire frames of my improved crate, each of which is formed from a continuous length of steel wire of the requisite gage, in accordance with the size and capacity of the crate. To the 45 wire marginal bottom frame member, the strands of the reticulated bottom 7 of the crate are suitably secured by turning or clenching the same upon said wire. The longitudinal parallel portions of the top and bottom wire members 5 and 6 are also connected by the wire mesh side walls 8. In the 50 accompanying drawing, I have shown the wire mesh walls of the crate as constructed of strands of wire running at right angles to each other in horizontal and vertical directions.

To the ends of the top marginal frame wire 5 of the crate, the reticulated end sections 9 are connected by turning the upper ends of the vertical wire strands thereon, as indicated at 11, so that said end sections may be swung upon the ends of the marginal frame wire 5 and raised or lowered. At the free end of each of the end sections 10 of the crate, an additional horizontal wire 11' is woven in the wire fabric, and this additional wire is adapted to be engaged by the free ends of the hook members 12 which are set up as shown in Fig. 1, and the lower ends of the end sections 10 of the crate are secured by means of the hooks 12, the several parts of the crate being held in erect position and against collapse.

When it is desired to collapse the crate or receptacle, the hooks 12 are disengaged 75 from the wires 11 of the end sections of the frame and these end sections are swung upwardly and outwardly. The top marginal wire 5 is then forced laterally so that the sides 8 of the frame will swing downwardly, 80 one of said sides resting upon the bottom of the frame while the other side will project laterally therefrom and in the same plane with said bottom. The end sections 10 of the frame are then swung inwardly 85 over the latter side section and upon each other, as clearly shown in Fig. 2 of the drawing. The several parts of the crate structure are thus very compactly arranged so that a large number of the crates can be stored in 90 a comparatively small space. The crate may be constructed in any desired capacity and the size or gage of the marginal wires and the wires of the several crate sections varied 95 accordingly. The crate is also extremely durable as well as light in weight, and may be conveniently moved from place to place.

Having thus fully described my invention, what I desire to claim and secure by Letters Patent is:—

A collapsible crate including top and bottom rectangular marginal frame wires, wire mesh side sections permanently connected to the longitudinal portions of said marginal wires, a wire mesh bottom secured upon the bottom marginal wire, wire mesh end sections permanently connected to the ends of the top marginal wire for swinging movement with respect thereto, said side sections of the crate being adapted for lateral swinging movement upon the sides of the lower marginal wire, and said end sections being

adapted to be swung inwardly over the top marginal wire and upon each other when the crate is collapsed, and hook members on the ends of the bottom marginal wire for engagement with the free ends of the wire end sections of the crate to retain the several parts of the crate in erect position.

In testimony whereof I hereunto affix my signature in the presence of two witnesses.

ALVIN D. BROWN.
